(57) **CLAIM**

I claim the ornamental design for a magnetic collar link, as shown and described.

DESCRIPTION

FIG. 1 is a right top perspective view of the magnetic collar link showing an elongated portion and a link portion connected.

FIG. 2 is a bottom left perspective view of the magnetic collar link.

FIG. 3 is a top elevation view of the magnetic collar link.

FIG. 4 is a bottom elevation view of the magnetic collar link.

FIG. 5 is a side elevation view of the magnetic collar link.

FIG. 6 is a front elevation view of the magnetic collar link, without the elongated portion.

FIG. 7 is a rear elevation view of the magnetic collar link, without the elongated portion.

FIG. 8 is a top left perspective view of the magnetic collar link showing the elongated portion and the link portion separated.

FIG. 9 is a bottom right perspective view of the magnetic collar link showing the elongated portion and the link portion separated.

FIG. 10 is an alternative side view of the magnetic collar link showing the elongated portion and the link portion separated.

FIG. 11 is an alternative top elevation view of the magnetic collar link showing the elongated portion and the link portion separated.

FIG. 12 is an alternative bottom elevation view of the magnetic collar link showing the elongated portion and the link portion separated.

FIG. 13 is an alternative front right perspective view showing the elongated portion separated from the link portion, and the link portion further separated into a lower magnet portion and an upper crest portion.

FIG. 14 is an alternative bottom left perspective view showing the elongated portion separated from the link portion, and the link portion further separated into the lower magnet portion and the upper crest portion; and,

FIG. 15 is an alternative side elevation view showing the elongated portion separated from the link portion, and the link portion further separated into the lower magnet portion and the upper crest portion.

The broken line showing of portions of the magnetic collar link is included for the purpose of illustrating environmental structure and forms no part of the claimed design.
